FUEL ENRICHING MEANS

Chester F. Johnson, Detroit, Mich.

Application March 21, 1930. Serial No. 437,666

5 Claims. (Cl. 123—119)

This invention relates to improvements in carburetors for internal combustion engines and has special reference to the provision of improved priming arrangements automatically brought 5 into action as by the last part of the movement of the usual choke control.

It is well known that the starting requirements of internal combustion engines vary in accordance with engine and external temperatures, a very rich and consequently almost raw 10 fuel priming charge facilitating the starting of cold engines. Choking the air supply serves to enrichen the mixture sufficiently for normal or favorable conditions but an additional priming 15 charge facilitates starting under unfavorable conditions. It is accordingly an object of this invention to provide an improved and simplified priming device cooperating with and supplementing the action of the normal choking control 20 and under the same control so that the action thereof can be available as desired.

It is another object of this invention to provide a carburetor having a priming device delivering fuel above the throttle, the priming device 25 having a normally open air bleed serving as an economizer under operating conditions and at the same time nullifying the effect of suction on the priming device, the closing of the air bleed imposing manifold suction on the priming 30 device and thus causing the delivery of fuel therefrom.

Other and further important objects of this invention will be apparent from the disclosures in the specification and the accompanying drawings.

This invention (in a preferred form) is illustrated in the drawing and hereinafter more fully described.

On the drawing:

40 Figure 1 is an elevation of a carburetor incorporating a priming device embodying the features of this invention.

Figure 2 is a fragmentary section on the line II—II of Figure 1.

45 Figure 3 is a fragmentary detail section on the line III—III of Figure 1.

As shown on the drawing:

An air valve type of carburetor has been chosen to illustrate a specific embodiment of 50 this invention although it is to be understood that this invention is equally applicable to other types of carburetors, one phase of the invention comprising a cooperative action between the priming system and the carburetor choke valve.

55 In the air valve carburetor illustrating this in-

vention a body 10 has a mixture outlet passage 11 controlled by a throttle valve on a shaft 12, a float bowl 13 therebelow supplying fuel to a primary mixing system, not shown, to which secondary air is added from a flap air valve 14 backed by a spring 15 between two seats 16 and 17. The lower seat 17 is movable and has a downwardly extending stem 18 engaged by an arm 19 associated with a choke control lever 20. When the choke control lever is moved nearly 65 to its dotted line position in Figure 1 the lower spring seat 17 is lifted to compress the spring 15 to hold the air valve closed. The foregoing structure is in effect a combined air valve and a choke valve since holding the valve 14 closed 70 against increased suction gives the same result as closing a butterfly choke valve in the air intake to a carburetor.

In the carburetor chosen for illustrative purposes an air pump, indicated as a whole by the 75 reference numeral 21, is interconnected with the throttle and acts to increase the air pressure above the fuel in the float bowl when the throttle is opened suddenly. This particular accelerating arrangement requires a slight modification of 80 the priming device hereinafter to be described, which modification would not be necessary if the air pressure above the fuel were not increased to cause the temporary delivery of a supplemental fuel charge through the normal 85 nozzle system.

An air bleed passage 22 opens into the mixture passage 11 above the throttle therein and normally receives its air supply through a larger 90 vertical passage 23 open at its lower end. The upper end of a priming tube 24 is centered in 95 and in spaced relationship to the passage 23 and a collar 25, sliding on the tube 24, serves as an air bleed valve to close the lower end of the passage 23, cutting off the inflow of air and thus imposing manifold suction on the priming tube.

The lower end of the tube 24 is threaded into a passage 26 in the float bowl body, which passage 26 is in communication with the fuel in 100 the float bowl through a restricted orifice 27. Thus when the collar 25 cuts off the air bleed 105 the manifold suction draws fuel from the float bowl through the orifice 27, passage 26 and tube 24 delivering the priming fuel into the manifold through the air bleed passage 22.

The effect of the air pressure accelerating pump is to cause the ejection of increased quantities of fuel through the available fuel outlets 110 including the orifice 27, so that the capacity of 115

the tube 24 and passage 26 must be proportioned to the delivery through the orifice 27 due to the operation of the accelerating pump in order to prevent the pump from ejecting fuel from the top of the tube 24. The restricted inlet orifice 27 thus prevents such overflow while supplying sufficient fuel for priming purposes due to the high manifold suction created by starting with the choke closed.

The collar or valve 25 is arranged to be lifted into closing engagement in the passage 23 by the last part of the closing movement of the choke operating lever 20 corresponding to the "all out" position in the case of the usual pull type of dash control. To accomplish this result an arm 28 is formed on the lever 20 and engages beneath an offset spring seat 29a formed on a lever 29 pivoted on the choke control shaft 30 carrying the arm 19 and lever 20. The outer end of the lever 29 is linked to the collar 25 by a rod 31. The lever 29 is normally held in its lower full line position by a spring 32 and is only moved upwardly when the choke lever arm 28 approaches the limit of its motion and makes contact with the spring seat on the lever thus lifting the collar 25. With this arrangement the priming device of this invention is brought into action after the choke is fully effective and the operation thereof is optional with the operator.

In starting an engine under moderately cold conditions it may only be necessary to partially pull out the choke control to increase the resistance to opening of the air valve which increased resistance to opening increases the fuel delivered through the normal fuel system, the priming device remaining inoperative. Under severe conditions the very last part of the choker control movement operates through the lever 29 and rod 31 to lift the collar or valve 25 and thus puts the fuel chamber in direct communication with the mixture passage above the throttle, the suction at this point being very high when the motor is cranked over with the air valve held closed to act as a choke. This high suction induces a flow of fuel from the float chamber through the tube 24 and passage 22, which fuel, when added to that produced by the choking arrangements, produces a very rich mixture, a part of which is delivered well above the throttle and thereby insures a very prompt starting of the engine.

It will thus be seen that I have provided an improved and simplified priming device which comes into action after the usual choke is in full operation and has been found insufficient as in severely cold weather.

I am aware that many changes may be made and numerous details of construction may be varied through a wide range without departing from the principles of this invention, and I, therefore, do not purpose limiting the patent granted hereon otherwise than necessitated by the prior art.

I claim as follows:

1. In a carbureter including a fuel chamber,

a mixture outlet containing a throttle valve and a choke controlled air supply, a priming passage leading from below the fluid level in said fuel chamber to the mixture outlet above the throttle therein, means comprising an air bleed into said priming passage to normally render the same inoperative, and means for closing said air bleed to subject the priming passage to the suction in the mixture outlet above the throttle therein. 80

2. In a carbureter including a fuel chamber, a mixture outlet containing a throttle valve and a choke controlled air supply, a priming passage leading from below the fluid level in said fuel chamber to the mixture outlet above the throttle therein, means comprising an air bleed into said priming passage to normally render the same inoperative, means for closing said air bleed to subject the priming passage to the suction in the mixture outlet above the throttle therein, and means associated with the choke for operating the choke and also the means for closing the air bleed during the last part of the movement of the choke control. 85

3. A carbureter, including a fuel chamber and mixture outlet passage, a priming passage connecting the mixture outlet passage to the fuel chamber beneath the liquid level therein whereby suction at the mixture outlet is adapted to draw fuel through the priming passage, an air bleed opening into said priming passage and adapted when open to prevent the action of suction on the fuel in said float chamber, and means for closing said air bleed to cause the priming passage to deliver fuel from said float chamber to the mixture outlet passage. 90

4. A carbureter including a fuel chamber and a mixture outlet passage, a priming passage connecting the mixture outlet passage to the fuel chamber beneath the level of the fuel therein whereby suction at the mixture outlet is adapted to draw fuel through the priming passage, an air bleed into said priming passage, choking means for the carbureter adapted to increase the suction in said mixture outlet passage, and means associated with the choking means for closing said air bleed to cause the priming passage to deliver fuel from said fuel chamber. 95

5. A carbureter including a fuel chamber and a mixture outlet passage, a priming passage connecting the mixture outlet passage to the fuel chamber beneath the level of the fuel therein whereby suction at the mixture outlet is adapted to draw fuel through the priming passage, an air bleed into said priming passage, choking means for the carbureter adapted to increase the suction in said mixture outlet passage, and means in cooperation with said choking means for closing said air bleed during the last part of the closing movement of said choking means to cause the priming passage to deliver fuel from said fuel chamber. 100

CHESTER F. JOHNSON.
